(57) **CLAIM**

The ornamental design for a hard shell, multi-article, reclosable package, as substantially shown and described.

DESCRIPTION

FIG. 1 is a front perspective view of a first embodiment of a hard shell, multi-article, reclosable package, showing our new design and with the lid and package in a closed position;

FIG. 2 is a front perspective view of a reclosable packaging shown in FIG. 1 with the reclosable lid in an opened position.

FIG. 3 is a side perspective view of the reclosable packaging shown in FIG. 1 in an unfolded configuration.

FIG. 4 is a top view of the reclosable packaging shown in FIG. 1.

FIG. 5 is a bottom view of the reclosable packaging shown in FIG. 1.

FIG. 6 is a front elevational view of the reclosable packaging shown in FIG. 1.

FIG. 7 is a rear elevational view of the reclosable packaging shown in FIG. 1.

FIG. 8 is a left side elevational view of the reclosable packaging shown in FIG. 1.

FIG. 9 is a right side elevational view of the reclosable packaging shown in FIG. 1.

FIG. 10 is a front perspective view of a second embodiment of a hard shell, multi-article, reclosable package, showing our new design and with the lid and package in a closed position;

FIG. 11 is a top view of the reclosable packaging shown in FIG. 10.

FIG. 12 is a bottom view of the reclosable packaging shown in FIG. 10.

FIG. 13 is a front elevational view of the reclosable packaging shown in FIG. 10.

FIG. 14 is a rear elevational view of the reclosable packaging shown in FIG. 10.

FIG. 15 is a left side elevational view of the reclosable packaging shown in FIG. 10; and,

FIG. 16 is a right side elevational view of the reclosable packaging shown in FIG. 10.

FIGS. 1-16 are various views of a hard shell, multi-article, reclosable packaging in accordance with the present design. The reclosable packaging is adapted to contain multiple articles of a consumable product including confections such as mints. Features disclaimed with broken lines in the Figures indicate structure which forms no part of the claimed design.
